UNITED STATES PATENT OFFICE.

WILLIAM H. EMERY, OF BROOKLYN, NEW YORK, ASSIGNOR TO CHARLES G. EMERY, OF SAME PLACE.

CIGARETTE-MACHINE.

SPECIFICATION forming part of Letters Patent No. 308,556, dated November 25, 1884.

Application filed March 12, 1884. (No model.) Patented in England July 18, 1884, No. 10,303, and in Belgium July 18, 1884, No. 65,805.

To all whom it may concern:

Be it known that I, WILLIAM H. EMERY, a citizen of the United States, residing at Brooklyn, in the county of Kings and State of New York, have invented certain new and useful Improvements in Cigarette-Machines, (for which I have obtained Letters Patent in Great Britain, No. 10,303, dated July 18, 1884, and in Belgium, No. 65,805, dated July 18, 1884,) of which the following is a full, clear, and exact specification.

This invention relates to certain improvements upon the subject-matter of Letters Patent of the United States dated the 3d day of June, 1879, No. 216,164, and the 31st day of August, 1880, No. 231,779, for improvements in cigarette-machines in which loose tobacco is formed into a continuous filler and a continuous inclosing-wrapper applied around said filler, forming a continuous cigarette, which is fed forward and cut into suitable lengths, the entire series of operations being performed by automatic mechanism.

The patents above recited cover, so far as I know, the first inventions in which a cylindrical cigarette-body of proper dimensions and of indefinite length has been manufactured by automatic mechanism preparatory to its being cut into proper lengths to form the individual cigarettes ready for the market.

Heretofore, as fully set forth in the Letters Patent named above, machine-made cigarettes have been produced by throwing the tobacco by a picker upon an endless traveling belt, by which it is carried to a filler-chamber, wherein the belt is partially curved or wrapped around the tobacco. From this point it passes to a filler-forming chamber, wherein the traveling belt is carried completely around the superincumbent mass of tobacco and the proper circular form given to the cigarette-filler.

The succeeding steps in the process of manufacture are fully set forth in the Letters Patent named, and as they form no part of and are not directly connected with my present invention, it is not necessary to describe them here.

It is the purpose of my present invention to provide positive automatic mechanism for

tamping, compressing, and packing the tobacco upon the filler-forming belt at the point 50 where the latter enters the packing-chamber.

Heretofore the constant presence and manipulation of an attendant has been necessary both to spread the tobacco where it lies in unequal quantities and to tamp and pack it with 55 the fingers, in order to prevent the increased curvature of the belt and the lateral compression of the tobacco from pushing the filler, or some part thereof, beyond the approaching edges of the traveling tape.

To this end, therefore, my invention consists in the combination, with the traveling tape or filler-forming belt, of a tamping and compressing bar having vertical adjustment and acting intermittently upon the tobacco, to 65 tamp, compress, and pack the same within the upwardly-curving belt at the point where it passes through the packing-chamber and previous to its entering the filler-forming tube.

It is also the purpose of my present invention to provide means for using, in the formation of the filler, a filler-carrying belt of any suitable length, which is taken from a pay-off roll, and, after performing its function, received upon a take-up roll, in contradistinction to an 75 endless belt or tape such as has been used heretofore.

To this end, therefore, my invention also consists in the combination, with the filler-forming devices, of a single or divided belt, 80 a pay-off roll from which it is taken, and a take-up roll by which it is received, the latter being speeded to keep the belt constantly taut, and both pay-off and take-up rolls being interchangeable upon their bearings, to permit the tape being wound from one upon the other, and vice versa.

My invention finally consists in the several combinations and constructions of parts, which are fully hereinafter set forth, and definitely 90 pointed out in the claims.

Referring to the drawings, Figure 1 is a side elevation of the filler-forming mechanism, illustrating it up to the point where the filler leaves the belt and enters the filler-tube. Fig. 2 is a 95 plan view of a section of the table, with its at-

tachments, illustrating my packing devices. Fig. 3 is a detail perspective of the tamping, packing, and compressing bar detached. Fig. 4 is an end elevation, taken from the rear, of the tamping, packing, and compressing mechanism. Fig. 5 is a detail perspective of the bearing-post, with adjusting devices. Fig. 6 is a side elevation of the tamping, packing, and compressing mechanism, with its attachments. Fig. 7 is a similar view showing the packing-bar in a different position. Fig. 8 is an end elevation of the take-up and pay-off mechanism. Fig. 9 is a detail of the take-up roll.

15 A in said drawings represents the table upon which the operative parts of the mechanism have support. This table, which is of some length, is mounted upon metallic frame-supports B, by which I obtain great strength and 20 stability with lightness of structure. It is also a considerable advantage to form these parts of metal instead of wood, as I thereby avoid all shrinkage and warping, and the parts can be cast or rolled out, thereby affording duplicates of any detachable or separate portion. 25 At the end of the table is placed the picker-chamber, (shown in dotted lines in Fig. 1,) but which requires no description, as it forms no part of my present invention, and is fully 30 shown and set forth in prior patents.

C represents the filler-carrying belt or tape, which passes through the bottom of the picker-chamber, where it receives the tobacco which is to form the continuous filler. It passes 35 thence to the packing-chamber D, where the sides or edges of the belt are gradually rolled or curved upward, to give the proper cylindrical shape to the filler. This belt is taken from a pay-off roll, E, which is mounted upon a 40 journal or shaft carried by a frame, F, placed near the end of the table, and after accomplishing its function it is returned beneath the table, passing under and engaging with the driving-pulley A' and a tension-roll, a, to 45 a take-up roll, E', journaled upon the frame F, beneath the pay-off roll E. This take-up roll is driven by a belt, e, geared with a large pulley, E², upon the axis of the pay-off roll, and with a smaller pulley, E³, upon the axis 50 of the take-up roll E'. By this means the latter roll is speeded to such a degree that it exerts a constant tension upon the belt C, all excess of speed being compensated by the slip of the belt e upon one or both of its pulleys.

55 It will be seen by reference to Fig. 8 that the pay-off and take-up rolls are duplicates as to the large and small pulley with which each one is provided, the purpose of this construction being as follows: When the filler-carrying belt has been wholly taken from the pay-off roll E and wound upon the take-up roll E', by removing the journal-pins e', which retain them upon their shafts, the two rolls may be shifted in position, the take-up roll being 60 coming the pay-off roll, and being mounted upon the upper journal, while the pay-off roll,

from which the belt has been exhausted, is slipped upon the lower journal and becomes the take-up roll. This avoids the necessity of rerolling the belt after each feed, economizing 70 much time and trouble, and avoiding unnecessary wear upon the filler-carrying belt. For convenience in connecting the latter to the take-up roll, a notch or groove is made in the spool-body, as shown in Fig. 9, to receive 75 the end of the belt, after which a single revolution winds it over the secured end and holds it fast.

Upon the table, arranged transversely to the filler-carrying belt and a little in front of the 80 entrance to the packing-chamber D, I mount a shaft, G, in bearings g, and upon the extremity of this shaft is rigidly mounted or keyed a sprocket-wheel, H. Sleeved upon the same shaft, between the sprocket-wheel and 85 the bearing g, is one end of a carrier-bar, I, arranged parallel with the filler-carrying belt, and having support at its other end in a slotted post, K, where it rests upon a suitable spring, k, having sufficient tension to raise the 90 bar, and permitting its vertical adjustment by a set-screw, k', which is tapped through a yoke, k², pivoted to the top of the post.

Upon the carrier-bar, near its adjustable extremity, and in the same vertical plane as 95 the sprocket-wheel H, is mounted a second sprocket-wheel, H', and the two are connected by a chain-gearing, H², whereby motion imparted to the sprocket-wheel H by the shaft G will be accurately reproduced in the second 100 sprocket-wheel, H'.

I have shown in the drawings a tension-roll, h, carried by a bar, h', pivoted upon the carrier-bar I, for the purpose of giving such 105 accurate correspondence of rotation between the two sprocket-wheels. This is not, however, essential, as they may be properly geared with such a degree of tension as to dispense with any such device.

110 Upon the face of each sprocket-wheel, and eccentric to its axis, is placed a stud, i, tapped to receive a bearing-pin, i', and upon said studs is mounted a tamping, packing, and compressing bar, L. This bar is provided upon 115 its upper face with bosses l, which have a female thread to receive screw-eyes l', the latter being adapted to slip over the studs upon the sprocket-wheel, and be held thereon by the bearing-pins i', thus affording a convenient 120 means of adjusting the packing-bar vertically both as to the distance at which it shall act and to secure a substantial parallelism with the belt. This vertical adjustment of the bar enables me to adapt its action to the volume 125 of the tobacco lying upon the filler-carrying belt. This volume may vary, according to the size of cigarette to be made, and by means of the screw-eyes l' a very accurate and delicate adjustment is possible toward and from 130 the belt. By reference to Figs. 2 and 3 it will be seen that this bar is of somewhat

greater length than the packing-chamber, and that its smaller and projecting end extends into the throat of said chamber, and substantially fills the narrowing portion thereof.

5 The shaft G is driven by a belt from a central longitudinal shaft, S, which runs beneath the table from end to end thereof, and it rotates the sprocket-wheels in the same direction in which the filler-carrying belt is moving.

10 In this manner it will be seen that the tamping, packing, and compressing bar L will, as it descends toward the belt, also move with it, the sprocket-wheels, being geared to impart the proper speed to secure this result. More-

15 over, as the filler-carrying belt moves beneath the said bar the latter will act repeatedly upon the same portion of the filler before the movement of the belt has carried it beyond the action of the bar. By this repeated tamping and

20 packing the filler is compressed to the exact volume and form required to prepare it for the subsequent operations of the mechanism, and all the protruding shreds or filaments of tobacco are, under the action of the bar, drawn

25 under the bar and tamped down into the filler. The operation of this tamping, packing, and compressing bar is as follows: As already described, the filler-carrying belt as it enters the packing-chamber is gradually curved upward

30 until the tobacco resting thereon is rolled into cylindrical form. This upward rolling of the edges of the belt has a tendency to push the tobacco upward at the sides and above the edges of the belt. Heretofore hand manipulation has been required to tamp and compress the filler to avoid this tendency; but this labor is extremely fatiguing, and its employment adds materially to the cost of production.

35 The tamping and compressing bar L, therefore, is intended as a substitute therefor. It will be seen now that as the belt is being rolled and the filler gradually shaped the bar L will descend upon the tobacco and accomplish the same function heretofore effected by

40 manual labor. It has the great advantage, however, of compressing the filler to the same degree at each operation, and it operates, also, over a more extensive surface than could be covered by the hand of an attendant. As the

45 bar reaches the lowest point in its stroke its motion is coincident with the movement of the filler-carrying belt, and there is therefore no derangement of the tobacco, and no danger of the feed of the belt being interrupted. By

50 its use, also, the filler is packed and compressed into a perfectly-uniform shape, and the finished cigarettes are more perfect in shape and uniform in size, as well as being of far greater equality in the volume of tobacco

55 in each than any hand-made cigarettes, or cigarettes made upon machines where the filler is tamped and packed by the fingers of an attendant.

To provide for the speedy and easy removal of the tamping, packing, and compressing bar, should it become necessary to gain access to

the packing-chamber, or to arrest the operation of the device, the yoke k², pivoted to the post K, is thrown off the end of the carrier-bar I, and the latter may then be turned up into 70 the position shown in Fig. 1, the bar turning upon the shaft G, on which its end is sleeved. In this position it may rest upon the picker-chamber or any other suitable support, and it is entirely out of the way of the attendant for 75 all purposes.

I have shown in the drawings, and propose to use when desirable, a duplication of the operative parts described, one series being arranged upon each side of the table. 80

By reference to Fig. 2 it will be seen that both of the tamping, packing, and compressing bars are operated by the same shaft G, and by the construction described above either one or both may be used or not. The filler-carrying belts also are duplicated, and the journal-supporting frame F is provided with four bearings, two upon each side. These parts require no description, being exact duplicates of those already set forth. 85

It should be distinctly understood that I do not confine myself to a tamping, packing, and compressing bar having movement with the belt, as I may, within the limits of my invention, use any reciprocating device suitable for 90 the purpose, whether the movement be simply vertical or circular.

Although I have shown a single or divided belt in connection with the automatic tamping and compressing device, it is nevertheless 100 evident that I may use the ordinary endless belt therewith without any material change in my invention.

In the construction of the tamping, packing, and compressing bar L, I prefer to use a 105 highly-polished metal to which the oils of the tobacco or any viscous substance therein found will not readily adhere. For this same purpose, also, I may plate the bar with nickel or other metal, or may provide it with a coating 110 or covering of celluloid, zylonite, pyroxylite, or any similar material; or I may construct the bar wholly from such material. It should be noted that it is necessary to give a polished surface upon the tamping face and the 115 sides of the bar only, as these are the portions brought in contact with the tobacco.

It should be noted as one of the important results flowing from this invention that, inasmuch as the action of the automatic tamping, packing, and compressing mechanism is precisely uniform at each and every point, and for that reason forms a filler which is of greatly superior condition as regards its uniformity of size, volume, and shape throughout, the necessity for a careful and critical inspection of each individual cigarette when finished is in a great measure removed. This is the last and most important step in the process of manufacture, and the importance of effecting substantial economy in the labor and skill heretofore required therein is very great. 120 125 130

What I claim is—

1. In a cigarette-machine, the combination, with a traveling filler-carrying belt and a packing-chamber, of a tamping, packing, and compressing bar, and mechanism, substantially as described, for giving said bar intermittent action upon the tobacco, substantially as and for the purpose set forth.
2. In a cigarette-machine, the combination, with a filler carrying belt and a packing-chamber, of a tamping, packing, and compressing bar, and mechanism, substantially as described, for giving said bar motion toward and with the belt at intervals, substantially as and for the purpose set forth.
3. In a cigarette-machine, the combination, with the filler-carrying belt and the packing-chamber, of a tamping, packing, and compressing bar, and pulleys geared to rotate in unison, and eccentric pins by which said bar is carried, substantially as and for the purpose set forth.
4. In a cigarette-machine, the combination of a table, filler-forming devices thereon, a filler-carrying belt traveling over the table, and a pay-off roll and take-up roll, substantially as described.
5. In a cigarette-machine, the combination, with a filler-carrying belt which is fed from end to end, of a pay-off roll from which it is taken, a take-up roll upon which it is received, and gearing connecting said rolls together, whereby the take-up is speeded in excess of the motion of the pay-off roll, substantially as and for the purpose set forth.
6. In a cigarette-machine, the combination, with a filler-carrying belt, of a pay-off and a take-up roll, and mechanism, substantially as described, connecting the two rolls, and driving the take-up roll at a speed in excess of the feed of the belt, substantially as and for the purpose set forth.
7. In a cigarette-machine, the combination, with a filler-carrying belt, of a pay-off roll and a take-up roll, which are interchangeable, and means, substantially as described, where-

by the take-up roll, when full, may be made the pay-off roll, and vice versa, substantially as and for the purpose set forth.

8. In a cigarette-machine, the combination, with a transverse shaft, of a sprocket-wheel or other gear mounted thereupon, a carrier-bar having an end sleeved upon said shaft and the other supported by suitable devices, a sprocket-wheel or other gear mounted upon said bar, and geared to revolve with that upon the shaft, and a tamping, packing, and compressing bar carried by eccentrically-arranged pins upon said wheels, substantially as and for the purpose set forth.
9. In a cigarette-machine, the combination, with the sprocket-wheels and their eccentrics, of the tamping, packing, and compressing bar connected thereto by eyes fitting upon said pins, and having threaded shanks tapped into said bar, whereby the latter may have vertical adjustment, substantially as and for the purpose set forth.

10. In a cigarette-machine, the combination, with the carrier-bar sleeved upon a shaft at one end, of the slotted post containing a spring upon which the other end rests, and the pivoted yoke upon said post, provided with a set-screw bearing upon the upper edge of the bar, substantially as and for the purpose set forth.

11. In a cigarette-machine, the combination, with the filler-carrying belt, of the take-up and pay-off rolls, each having a large pulley upon one side of the spool, and a small pulley upon the other side, whereby the take-up is driven by the pay-off and the two rolls rendered interchangeable, substantially as and for the purpose set forth.

In testimony whereof I have hereunto set my hand in the presence of two subscribing witnesses.

WILLIAM H. EMERY.
